PHONOGRAPH STYLUS

Robert L. Deschamps, Wheaton, James P. Thomsen,
Mount Prospect, and Ronald G. Thielmann, Arlington
Heights, Ill., assignors to Shure Brothers Incorporated

Filed July 20, 1973, Ser. No. 381,066

Term of patent 14 years

Int. Cl. D14—99, 01
U.S. Cl. D26—14 D

FIG.1

FIG.2

FIG.3

FIG.4

FIG.5

FIG.6

FIG.7

FIG. 1 is a perspective view of a phonograph stylus showing our new design, as found in its inoperative condition;

FIG. 2 is a perspective view of a phonograph stylus, as found in its operative condition;

FIG. 3 is one side view thereof, the other side being substantially identical;

FIG. 4 is a front view thereof;

FIG. 5 is a top plan view thereof;

FIG. 6 is a rear view thereof; and

FIG. 7 is a bottom plan view thereof.

We claim:

The ornamental design for a phonograph stylus, as shown and described.
